KITE

Ramsey M. Cox, Corsicana, Tex.

Application October 25, 1945, Serial No. 624,440

14 Claims. (Cl. 244—153)

1

This invention relates to new and useful improvements in kites.

One object of the invention is to provide an improved kite which may be sold in a compact knock-down form and readily assembled for flying by juveniles and which, when assembled, will fly without collapsing and in a more efficient manner.

A particular object of the invention is to provide a kite having a stick skeleton and a marginal cord frame together with clips immovably fastened on the cord frame, whereby said clips are properly positioned to receive the ends of the sticks and also whereby, the kite membrane or covering may be fastened to the cord frame and the kite flown without injury to said membrane by slippage of the cord frame or displacement of either the sticks or the clips.

Another object of the invention is to provide an improved means of attaching the sticks of a kite to the marginal cord which includes a flexible clip, preferably formed of a piece of heavy paper having a strip of reinforcing fabric secured to its inner face and folded upon itself with a patch or gob of hard plastic material, such as sealing wax, embedded in the reinforcing fabric; the clip having an aperture extending therethrough surrounded by the plastic material and the stick having a shouldered pin on its end for insertion in the aperture and the marginal string extending through the patch, whereby the clip is permanently secured to and located on the marginal string and a substantial means of detachably connecting the end of the stick with the marginal string is provided.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a rear elevation of a kite constructed in accordance with the invention.

Fig. 2 is a front elevation of the same.

Fig. 3 is an elevation of the cord frame, bridle and tail loop, the membrane being illustrated by dotted lines.

Fig. 4 is a plan view of the blank from which the clip is formed.

Fig. 5 is a longitudinal sectional view of the clip in position on one end of a stick.

Fig. 6 is a transverse sectional view of the same, and

2

Fig. 7 is an isometrical view of one of the tail blocks.

In the drawings, the numeral 10 designates a stick skeleton of the usual design having inclined upright cross sticks 11 and 12 respectively and a transverse cross stick 13, all of said sticks crossing at a common point and being held together at this point by a small wire nail or similar fastening 14. Each stick is provided at each 10 end with a reduced pin 15 surrounded by a shoulder 16.

The kite is provided with a cord frame 17 which is shown in full lines in Fig. 3 and portions of which are shown in the other figures. This 15 frame defines the general shape of the kite. Paper clips 18, which will be hereinafter more fully described, are fastened on the frame against movement relatively thereof and each clip is provided with an aperture 19 for receiving 20 one of the pins 15, whereby the shoulder engages the clip and thus holds the frame in position as well as being held in position by said frame. The usual covering or membrane 20, which may be formed of paper or any other suitable material, is provided with marginal flaps 21 which are folded around the cord frame and glued or otherwise fastened to the face of said membrane, spaces being left between the flaps and notches 22 provided in the membrane in 25 such spaces for permitting free movement and manipulation of the clips. This arrangement disposes the stick skeleton on the rear side of the kite and it has been found that by folding the flaps 21 over the face of the membrane, a more 30 substantial kite is provided and it is subject to less tearing and disintegration.

It is pointed out that by withdrawing the fastening 14 and pulling the clips off the ends of the sticks, said sticks may be disposed in parallel 40 relation in a bundle and the membrane wrapped therearound, whereby a compact package is provided. The kite is readily assembled by unrolling the membrane 20 and engaging the clips 18 on the pins 15 of the sticks. The sticks can then be 45 adjusted and the pin 14 placed in position. By fastening the clips against movement on the cord frame, and making the pins 15 of sufficient length, both the frame and the membrane are stretched and the parts are permanently held in 50 position. It has been common practice to attach the sticks directly to the cord frame and this does not secure them against displacement and consequent collapsing of the kite.

The kite is provided with a string bridle 23 55 which may be attached to the ends of the sticks

11 and 12 or to the cord frame adjacent the pins 15. A string tail loop 24 may be attached to the lower ends of the sticks 11 and 12 or to the cord frame thereat. I prefer to make the cord frame, the bridle and the tail loop from a single piece of string, and this can be done by attaching one end of the string to the clip 18 at the top of the stick 11 (Fig. 2) and then passing this string downwardly to the clip at the lower end of the stick 12 to form the left-hand side of the frame, then across the bottom of the frame and through the clip at the bottom of the stick 11, thence up the left side of the frame through the clip at the top of the stick 12 to the clip 18 at the top of the stick 11, then downwardly to the clip at the bottom of the stick 12, leaving sufficient slack to form the bridle loop; thence from the clip at the bottom of stick 12 downwardly to form the tail loop 24, then upwardly through the clip at the bottom of the stick 11 with the upper end secured in the clip at the top of the stick 12. This will leave two strings in front of the membrane 20 with sufficient slack to tie a knot 25, which forms a bridle loop 26, as will be obvious.

By tying a knot in the tail loop 24, an eye 27 may be formed and the upper end of a tail string 28 tied in this eye. To form the tail of the kite, a plurality of small spaced blocks 29 are provided. Each block is formed with inclined slots 30 and by engaging the string 28 in these slots from opposite sides of the block, each block is fastened on the string. While only two blocks have been shown, it is to be understood that a suitable number may be used.

One of the important features of the invention is the clip 18. This clip could be made of various materials and secured on the cord frame in any suitable manner. However, in the interest of economy, flexibility and security, I prefer to form the clip of a rectangular piece of wrapping paper and to glue or otherwise secure to one face thereof, a coarse mesh fabric 31 such as cheese cloth to reinforce the clip and to provide a rough inner surface when the blank is folded upon itself. The blank is formed with a pair of holes which register and form the aperture 19 when the blank is folded. Before the blank is folded, a patch or gob 32 of plastic material is deposited in the central portion so that when the blank is folded, the plastic will adhere to the fabric reinforcing and secure the clip together. It is desirable to use a plastic which may be applied in a molten state and which will dry in the form of a hard plastic, and ordinary sealing wax has been found satisfactory for this purpose. Any suitable means can be employed for forming the aperture 19 through the plastic patch when the clip blank is folded.

In applying the clips, the cord frame and other strings are embedded in the plastic before the blank is folded so that when the plastic hardens, the clip will be securely fastened on the cord frame and the other strings secured therein. It is obvious that by providing the gaps 22, the clips may be readily manipulated to engage the pins 15 in the apertures 18 thereof. It will be observed that the sticks 11, 12 and 13 being attached to the clips 18 and the membrane 20 being cut out around said clips, the membrane is carried solely by the cord frame on which the clips are immovably fastened, thus any movement of the sticks or clips is not contributed to the membrane, and the latter is not torn or injured as in the usual construction.

The foregoing description of the invention is explanatory thereof and various changes in the size, shape and materials, as well as in the details of the illustrated construction may be made, 5 within the scope of the appended claims, without departing from the spirit of the invention.

What I claim and desire to secure by Letters Patent is:

1. A kite including, a cord frame, paper clips 10 containing a patch of hard plastic secured on the frame, each clip having an aperture, cross sticks having reduced ends engaging in the apertures of the clips, and a membrane covering the sticks and attached to the frame.
- 15 2. A kite including, a cord frame, paper clips each having a fabric reinforcing applied thereto and a patch of hard plastic secured therein in which the frame is embedded, each clip having an aperture extending therethrough, cross sticks 20 having shoulder pins at the ends engaging in the apertures of the clips, and a membrane covering the sticks and attached to the frame.
- 25 3. As a sub-combination in a kite, a clip including two layers of paper having a fabric reinforcing secured to their inner surfaces, and a patch of hard plastic secured between the reinforced layers, the clip having an aperture extending therethrough surrounded by the plastic.
- 30 4. A kite including, a marginal cord frame, clips immovably secured around the cord of the frame and permanently held against displacement thereon, each clip having an aperture, cross sticks within the frame having reduced ends engaging in the apertures of the clips, and a 35 membrane secured on the cord frame and having portions cut out at the clips and free from attachment to the clips.
- 40 5. A kite including, a marginal cord frame, folded paper clips, each containing a patch of hard plastic material in which the cord frame is permanently embedded and an aperture extending through the clip and the patch, a membrane secured on the cord frame free from attachment to the clips, and cross sticks overlying the membrane and having reduced ends inserted in the apertures of the clips.
- 45 6. A kite including, a cord constituting a marginal frame, clips secured on said cord at spaced intervals having means for immovably fastening 50 them on the cord, said clips having apertures, cross sticks having reduced ends engaging in the apertures of the clips, and a membrane covering the sticks and attached to the cord free of the sticks and clips.
- 55 7. A kite including, a cord constituting a frame, clips each folded upon itself and receiving the cord in its fold, each clip being immovably secured on the cord and having an aperture, cross sticks having reduced ends engaging in the apertures of the clips, and a membrane having its margin secured to the cord free of the clips.
- 60 8. A kite including, a cord constituting a frame, clips each consisting of a piece of reinforced paper folded upon itself and receiving the 65 cord in its fold, each clip being immovably secured on the cord and having an aperture, cross sticks having reduced ends engaging in the apertures of the clips, and a membrane having its margin secured to the cord free of the clips.
- 70 9. A kite including, a marginal cord frame, folded paper clips, each containing a patch of hard plastic material in which the cord frame is permanently embedded and an aperture extending through the clip and the patch, a membrane 75 secured on a cord frame free from attachment

to the clips, cross sticks overlying the membrane and having reduced ends inserted in the apertures of the clips, and a bridle cord having its ends embedded in the plastic material of certain of the clips.

10. A kite including, a marginal frame cord, flexible clips, each clip being folded upon itself around the cord, fastening means in each clip immovably holding it in place on the frame cord, each clip having an aperture, cross sticks having ends engaging in the clip apertures, and a membrane having its margin secured to the frame cord free of the clips.

11. A kite including, a marginal frame cord, flexible clips, each clip being folded upon itself around the cord, fastening means in each clip immovably holding it in place on the frame cord, each clip having an aperture, cross sticks having ends engaging in the clip apertures, a membrane having its margin secured to the frame cord free of the clips, and a bridle cord having its ends secured in the fastening means of certain of the clips.

12. As a sub-combination in a kite, a clip including two layers of paper, at least one of said layers having a fabric reinforcing, and a patch of hard plastic secured between said layers.

13. In a kite, cross sticks, a membrane covering the sticks, cord members attached to the sticks, a

paper clip including two layers of paper and a patch of hard plastic uniting said layers in which the cord members are embedded and secured between the paper layers.

14. In a kite, cross sticks, a membrane covering the sticks, a cord frame connected with the sticks, a bridle cord, and paper clips each including two layers of paper and a patch of hard plastic uniting the paper layers in which patch the bridle cord is embedded.
